(57) CLAIM

The ornamental design for a winged bandeau bra with cup forms, as shown and described.

DESCRIPTION

FIG. 1 is a rear view of a winged bandeau bra with cup forms showing the new design;

FIG. 2 is a front view thereof;

FIG. 3 is a left side perspective view of the winged bandeau bra shown in a state of use;

FIG. 4 is a right side perspective view thereof;

FIG. 5 is a top view thereof; and,

FIG. 6 is a bottom view thereof.

The stippling shown in FIGS. 1 and 3-5 illustrates adhesive on the interior surface of each wing that forms no part of the claimed design.

1 Claim, 6 Drawing Sheets
